SADIRON HANDLE STRUCTURE

Russell I. Huffman, Dover, Ohio, assignor to
 Knapp-Monarch Company, St. Louis, Mo., a
 corporation of Missouri

Application March 12, 1938, Serial No. 195,517

8 Claims. (Cl. 38—90)

As one of the objects of my present invention, I provide a sadiron structure having handles and handle supports of comparatively inexpensive and simple construction so arranged that the handle can be folded down against the iron itself when storing the iron, the iron being so constructed that it is relatively flat instead of having the usual arched or dome-like casing covering the sole plate.

More particularly it is my object to provide handle means for a relatively flat sadiron which can be conveniently folded to a compact position against the top of the sadiron, yet may normally be extended to a position well above the sadiron to avoid uncomfortable heating of the user's hand when using the iron.

Another object is to provide a sole plate having in it a heating element and to provide relatively flat cover means for the heating element which is secured to the sole plate and consists of a plurality of flat plates spaced from each other by spacers so as to provide between them, air spaces to prevent excessive heating of the cover means and in turn excessive radiation of heat to the user's hand, my construction being such that these objects are accomplished without the necessity of using a relatively high casing over the sole plate as in usual constructions.

A further object is to provide a handle which is longitudinally split and thereby comprises a pair of handle elements, each of which is connected by handle supports to the cover means for the sole plate in such manner that the handle supports cross each other. The handle supports have co-acting indentations to retain the handle normally in raised or operating position, the handle supports being swingable down to a position substantially parallel to the sadiron with the handle elements thereagainst, thereby reducing the overall height of the iron to a minimum when it is desirable to store it, the iron thereby being particularly adaptable for the use of travelers.

A further object is to provide a nose piece on the sole plate designed to prevent catching of the edges of the cover plates on the fabrics being ironed.

Still a further object is to provide the cover plates extended rearwardly to act as a heel rest and thereby in conjunction with the rear end of the handle to serve as a means to support the iron in upended position.

With these and other objects in view, my invention consists in the construction, arrangement and combination of the various parts of my sadiron, whereby the objects contemplated are at-

tained, as hereinafter more fully set forth, pointed out in my claims and illustrated in the accompanying drawing. Although the invention is susceptible of a variety of embodiments, it is unnecessary to fully describe and illustrate more than one in order to give a full understanding thereof, both from its structural and functional standpoints. Accordingly, I have illustrated a preferred and desirable embodiment of the invention in the accompanying drawing, in which:

Figure 1 is a plan view of a sadiron structure embodying my invention, showing in solid lines the handle in operating position and in dotted lines the handle in folded-down position.

Figure 2 is a side elevation thereof.

Figure 3 is a rear elevation thereof showing the handles folded down in dotted position.

Figure 4 is an enlarged sectional view on the line 4—4 of Figure 1 to show the connection of cover plates relative to each other with an air space between them; and Figure 5 is an end elevation of a modified form of handle for my sadiron structure.

On the accompanying drawing I have used the reference character S to indicate a sole plate, C a cover means for the sole plate and H a handle for the sadiron structure. The sole plate S is provided with a heating element groove 10 (see Figure 4) which may be of any desired or conventional shape to accommodate the heating element 12 therefor. By way of illustration I show the heating element consisting of a resistance ribbon 12 wrapped around an insulator 13 and insulated from the sole plate S by insulating material 14.

The heating element is retained in position by the cover means C which consists of three relatively flat plates 15, 16, and 17. A sheet of insulating material 18 is interposed between the plate 15 and the heating element 12 to avoid electrical contact between the heating element 12 and the plate. The terminal ends of the heating element are connected in any suitable manner with terminal prongs 19 which are partially housed by a guard 20. The usual iron cord plug (not shown) is adapted to be associated with the terminals 19 for conducting electricity to the heating element of the iron.

The cover plate 15 is provided with a plurality of spaced upstanding indentations 21, while the plate 17 is provided with similar downwardly projected indentations 22. The indentations 21 and 22 are perforated and are spaced from each other. The indentations serve as a means to space the plates 15, 16 and 17 so that air can circulate between them, thus reducing the radiation 55

of heat from the sole plate to the hand of the user during use of the iron. The plates 15, 16 and 17 are connected together by countersunk rivets 23 extending through the perforated indentations 21 and 22 as best shown in Figure 4.

5 The entire cover assembly consisting of the plates 15, 16 and 17 is secured in position on the sole plate S by screws 24 extending into threaded openings 25 of the sole plate. Indentations 21a and 22a are provided in alignment with each other to retain the spacing between the plates where the screws 24 extend through them.

10 The sole plate S has at its front end upwardly projecting flanges 26 which serve as a guard over the front ends of the cover plates 15, 16 and 17 to eliminate the possibility of fabrics being ironed 15 catching thereon.

15 The handle H is longitudinally split and consists of a pair of handle elements 27 normally aligned with each other by means of dowel pins 28 entering sockets 29 thereof. As an alternative, the handle elements 27 can, as illustrated by those shown as 27a in Figure 5, be formed with coacting tongues 28a and grooves 29a extending 20 throughout their lengths in place of the pins and sockets of the previous figures. In the ends of the handles H, sleeves 30 are mounted, while on the cover plate 17 projections 31 are provided which have sockets 32. Handle supports 33 are 25 provided which have at their upper and lower ends respectively trunnions 34 and 35 pivotally received in the sleeves 30 and in the sockets 32 respectively. The projections 31 are suitably secured to the plate 17 as by rivets 36.

30 The projections 31, it will be noted, are laterally spaced and the handle supports 33 cross each other before entering the sleeves 30 (see Figure 3). In the raised or upstanding positions of the supports, coacting indentations 37 thereof serve 35 to normally retain them in position with the handle elements 27 engaged with each other. The handle supports 33 are made of spring wire or the like so that they can be assembled by springing the trunnions 35 into the bores 32 after the supports have been associated with the handle elements 27 and thereafter the handle supports, due to their resiliency, are biased to a position with the indentations 37 engaging each other. Accordingly the handle H is normally retained in 40 operating position but the two elements 27 can be forcibly separated manually and the handles swung to the dotted positions of Figures 1 and 3 when it is desirable to store the iron away. The wires 33 are suitably bent so that they clear the projections 31 in their folded down position. When folded down they are substantially parallel 45 to the cover plates and the handle elements 27 are in a position lying on the cover plates. This makes the overall height of the iron very little 50 as the sole plate and its cover means are relatively flat. The cover means extends rearwardly as is evident from an inspection of Figure 2 so as to form a heel rest. A line 38 is indicated touching the heel rest and the rear end of the handle H. 55 This line indicates the surface on which the sadiron is supported when in upended position, the heel rest and the rear end of the handle serving as a three-point support therefor as indicated at 39, 40 and 41 with the center of gravity of the 60 iron falling substantially centrally relative to the three points of support.

65 Due to the arrangement of the handle supports crossing each other, sufficient height for the handle is secured without excessive width 70 of the iron when the handles are folded down.

The relatively flat character of the sole plate and its cover means is a further feature contributing to compactness when folded, while the spaced cover plates effectively permit radiation of the heat to the atmosphere without excessive radiation in the direction of the handle. As the iron is passed over the fabric being ironed, the air circulating between the plates carries the heat away instead of permitting it to radiate toward the handle, whereas most of the heat is reflected 10 toward the ironing surface of the sole plate by the insulation 18 and the plate 15 which is preferably polished on its lower surface to aid in its heat reflecting properties.

15 Some changes may be made in the construction and arrangement of the parts of my sadiron without departing from the real spirit and purpose of my invention. Therefore I intend to cover by my claims, any modified forms of structure or use of mechanical equivalents which may 20 be reasonably included within their scope.

I claim as my invention:

1. In a sadiron structure, a sole plate, a heating element therein, cover means for said heating element, a pair of handles for said sadiron, 25 handle supports for said handles, said handle supports being pivoted at laterally spaced points to said cover means whereby said supports and handles can be swung downwardly to a position with the handle supports substantially parallel to the cover means and the handles thereadjacent, each of said handles being across the longitudinal center line of said cover means from the pivotal connection of its handle support thereto in both the upward and downward positions of said handles. 30

2. In a sadiron structure, a sole plate, a heating element for said sole plate, substantially flat cover means for said sole plate and having projections extending therefrom, a handle for said sadiron structure, said handle being longitudinally split and thereby comprising a pair of handle elements, handle supports for said handle elements, said handle supports being pivoted at their upper ends to said handle elements and at their lower ends to said cover means at laterally spaced points, said handle supports being arranged to cross each other and having coacting means in such position of the handle supports to hold the handle elements together, said handle supports having trunnions at their upper and lower ends pivotally mounted in the ends of the handle elements and in said projections, said trunnions having their axes arranged longitudinally of said sole plate and said handle elements having sleeves receiving the trunnions at the upper ends of said handle supports. 45

3. In a sadiron structure, a sole plate, a heating element for said sole plate, cover means for said sole plate, a handle for said sadiron structure, 60 said handle being longitudinally split and thereby comprising a pair of handle elements, handle supports for said handle elements, said handle supports being pivoted to said handle elements and to said cover means, and means to prevent vertical movement of said handle elements relative to each other when in position for operation. 65

4. In a sadiron structure, a substantially flat sadiron body, a heating element therefor, a handle for said sadiron body, said handle being longitudinally split and thereby comprising a pair of handle elements, handle supports for said handle elements, said handle supports being pivoted at their upper ends to said handle elements 70

and pivoted at laterally spaced points to said cover means, said handle elements having coacting means to align them with each other to prevent relative sliding movement.

5. In a sadiron structure, a sadiron body, heating means therefor, a handle for said sadiron structure, said handle being longitudinally split and thereby comprising a pair of handle elements, handle supports for said handle elements, 10 said handle supports being arranged to cross each other in all positions thereof, said handle supports being pivoted at their lower ends to said sadiron body and so related to their pivotal means as to permit said handle elements to assume position closely adjacent said body, and 15 means to prevent relative vertical movement of said handle elements when in their upward position for use.
6. In a sadiron structure, a sole plate, a heating element for said sole plate, a handle for said 20 sadiron structure, said handle being longitudinally split and thereby comprising a pair of handle elements, handle supports for said handle elements, said handle supports being pivoted at 25 their upper ends to said handle elements and pivoted at laterally spaced points to said cover means, said handle supports being arranged to cross each other and having coacting indentations to hold them normally in raised position, 30 said handle elements having coacting means in such position of the handle supports to align the handle elements with each other.

7. In a sadiron structure, a sole plate, a heating element for said sole plate, a handle for said sadiron structure and longitudinally split to thereby provide a pair of handle elements, handle supports for said handle elements, said handle supports being connected at their upper ends to said handle elements and having trunnions at their lower ends, trunnion receiving elements on said sadiron structure, said handle elements crossing each other in all relative positions thereof and formed with bent portions intermediate said trunnions and said handle elements to clear said trunnion receiving elements and thereby permit said handle elements to assume a position closely adjacent said sadiron structure when in 15 folded position.

8. In a sadiron structure, a sole plate, a heating element for said sole plate, a handle for said sadiron structure, said handle being longitudinally split and thereby comprising a pair of handle elements, handle supports for said handle elements, said handle supports being connected at their upper ends to said handle elements and pivoted at their lower ends to said cover means and being arranged to permanently cross each other and prevent uncrossing thereof and means of coaction between said handle elements to prevent relative vertical movement between them when in position for ironing operations.

RUSSELL I. HUFFMAN.
